DESIGN FOR A HEATER CABINET OR THE LIKE

Don F. Jones, Lansing, Mich., assignor to Motor Wheel Corporation, Lansing, Mich., a corporation of Michigan

Application April 13, 1935, Serial No. 56,360

Term of patent 7 years

To all whom it may concern:

Be it known that I, Don F. Jones, a citizen of the United States, residing in Lansing, county of Ingham, and State of Michigan, have invented a new, original, and ornamental Design for a Heater Cabinet or the like, of which the following is a specification, reference being had to the accompanying drawing, forming a part hereof.

In the drawing:

Figure 1 is a front view in elevation of a heater cabinet showing my new design;

Figure 2 is a side view in elevation of the heater cabinet shown in Figure 1; and

net shown in Figures 1 and 2.

I claim:

The ornamental design for a heater cabinet,
or the like, as shown.

DON F. JONES.
